CLAIM

The ornamental design for a light fixture, as shown and described.

DESCRIPTION

This application is related to U.S. patent application Ser. No. 15/144,315, filed on May 2, 2016, and U.S. patent application Ser. No. 29/609,266, filed on Jun. 29, 2017. It is understood that any material in U.S. patent application Ser. No. 15/144,315 and 29/609,266 that is not present in this application forms no part of the claimed design.

FIG. 1 is a top, front perspective view of a light fixture showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines depict unclaimed subject matter only and form no part of the claimed design. The features shown in long dash-short dash bolded broken lines indicate the bounds of the claimed design and otherwise form no part of the claimed design, with brackets indicating indeterminate length of the claimed subject matter.
